UNITED STATES PATENT OFFICE.

STEPHEN P. BURDICK, OF NEW YORK, N. Y.

IMPROVEMENT IN WOOD-SCREWS.

Specification forming part of Letters Patent No. **137,414**, dated April 1, 1873; application filed February 26, 1873.

To all whom it may concern:

Be it known that I, STEPHEN P. BURDICK, of the city, county, and State of New York, have invented a new and useful Improvement in Screws; and I do hereby declare the following to be a full, clear, and exact description thereof, which will enable those skilled in the art to make and use the same, reference being had to the accompanying drawing forming a part of this specification, in which drawing—

Figure 1 represents a side view of my invention. Fig. 2 is a section of the same in a larger scale than the previous figure; and Fig. 3 is a plan of a piece of timber, showing the opening produced by my screw. Fig. 4 is an edge view of the harpoon-point shown in Fig. 1.

Similar letters of reference indicate corresponding parts.

This invention consists in a screw with a thread composed of two members combined so that the outline of each thread presents the shape of an ovolo, and thereby a screw is obtained which can be driven home in wood without tearing the fibers, and which, when driven home, is firmly retained by the fibers catching in the recesses and against the shoulders of the succeeding threads so that the same can only be withdrawn by turning it in the proper direction. The point of my screw is harpoon-shaped, so that the same on being driven into wood will cut the fibers, and that the free ends of said fibers produced by the action of said harpoon-shaped point are enabled to spring into the recesses of the succeeding screw-thread, thereby retaining the bolt firmly in position.

In the drawing, the letter A designates my screw, each thread a of which consists of two members, b c, the outlines of which, when combined, have the shape of an ovolo. (Best seen in Fig. 2.)

The pivot d of my screw is harpoon-shaped so that the same on being driven down into a piece of timber will cut the fibers, as shown

in Fig. 3, and as the screw is driven down the free ends of the fibers produced by the cutting-point turn down and wedge themselves into the recesses of the screw-thread, as indicated in Fig. 1. The form of the members of my screw-thread is such that the same on being driven down into a piece of timber will not tear off the fibers, but it will simply crowd said fibers apart, and when the downward motion of the screw ceases the fibers in attempting to reassume their original position wedge themselves into the recesses c and against the shoulders formed at the junction of the members c and b of the successive threads, and the screw cannot be drawn out except by turning it round in the proper direction.

The flat surface of my harpoon-shaped point forms a lock, which prevents the screw from turning round spontaneously, and the shoulders or side points e e of said point form wedges which force the wood apart whenever sufficient power is applied to turn the screw, and thus my screw can be readily turned in or out without splitting the wood.

Above the points e e is formed a sunken or depressed neck, f, so that as the screw is forced into the wood the fibers of the same immediately crowd into said neck in an unbroken state, and the fiber is thus prepared for the further passage of the ovolo screw-threads through or down into the wood.

What I claim as new, and desire to secure by Letters Patent, is—

1. A screw having ovolo screw-threads, as herein shown and described, for the purpose specified.
2. A screw having a harpoon-point d e e, as shown, and ovolo screw-threads, as set forth.
3. A screw having the depressed or sunken neck f and harpoon-point d e e, substantially as herein shown and described.

S. P. BURDICK.
